US00D862112S

(12) **United States Design Patent** (10) Patent No.: **US D862,112 S**
(45) Date of Patent: ** Oct. 8, 2019

(54) **DISPENSER**

(71) Applicant: **GOJO Industries, Inc.**, Akron, OH (US)
(72) Inventors: **Andrew P. Tojek**, Garfield Heights, OH (US); **Brian T. Milliff**, Kirtland, OH (US)
(73) Assignee: **GOJO Industries, Inc.**, Akron, OH (US)

(**) Term: **15 Years**

(21) Appl. No.: **29/578,350**

(22) Filed: **Sep. 21, 2016**

(51) LOC (12) Cl. **23-02**

(52) U.S. Cl.

USPC **D6/545**

(58) **Field of Classification Search**

(57) **CLAIM**

The ornamental design for a dispenser, as shown and described.

DESCRIPTION

FIG. 1 is a top front, right side perspective view of a dispenser showing our new design;
FIG. 2 is a front plan view thereof;
FIG. 3 is a rear plan view thereof;
FIG. 4 is a left side elevational plan thereof;
FIG. 5 is a right side elevational plan view thereof;
FIG. 6 is a top plan view thereof;
FIG. 7 is a bottom plan view thereof;
FIG. 8 is a top front, right side perspective view of the dispenser with a drip tray;
FIG. 9 is a front plan view thereof;
FIG. 10 is a rear plan view thereof;
FIG. 11 is a left side elevational plan view thereof;
FIG. 12 is a right side elevational plan view thereof;
FIG. 13 is a top plan view thereof; and,
FIG. 14 is a bottom plan view thereof.

The broken lines shown in the figures represent portions of the dispenser that form no part of the claimed design.

1 Claim, 10 Drawing Sheets
